CLAIM

The ornamental design for a model car, as shown and described.

DESCRIPTION

FIG. 1 is a front and top perspective view of a model car, showing my new design;
FIG. 2 is another front and top perspective view thereof;
FIG. 3 is a rear and top perspective view thereof;
FIG. 4 is another rear and top perspective view thereof;
FIG. 5 is an enlarged front elevation view thereof;
FIG. 6 is an enlarged rear elevation view thereof;
FIG. 7 is a left side elevation view thereof;
FIG. 8 is a right side elevation view thereof;
FIG. 9 is a top plan view thereof; and,
FIG. 10 is a bottom plan view thereof.
The color shown in the figures forms no part of the claimed design.
